APPARATUS FOR REMOVING PLASTER
FROM PLATE GLASS SURFACING TABLES

John D. McLeod, Oakmont, and Harry A. Reynolds, Ford City, Pa., assignors to Pittsburgh Plate Glass Company, a corporation of Pennsylvania

Application November 1, 1935, Serial No. 47,896

5 Claims. (Cl. 15—93)

The invention relates to brush apparatus for removing plaster from the tops of tables employed in the continuous surfacing of plate glass. The glass is bedded in plaster of Paris, and after the removal of the glass, it is necessary to cut away the old plaster before applying a new layer. The objects of the present invention are to provide an improved brush construction for acting on the tops of the tables as they move therebeneath along their tracks, which is cheap, with low replacement cost for the parts worn away in service, which acts very efficiently to cut away the plaster, and which does not cut away the tops of the tables rapidly. One embodiment of the invention is illustrated in the accompanying drawings, wherein:

Figure 1 is a partial vertical section through the apparatus. Fig. 2 is a plan view of the supporting framework or spider. Figs. 3 and 4 are detail views of one of the brush holder plates, Fig. 3 being a plan view and Fig. 4 a section on the line IV—IV of Fig. 3. Figs. 5 and 6 are detail views of the other brush holder plate, Fig. 5 being a plan view and Fig. 6 a section on the line VI—VI of Fig. 5. And Figs. 7 and 8 are detail views of one of the clamping blocks, Fig. 7 being a side elevation, and Fig. 8 a plan view.

The framework or spider shown in Fig. 2 comprises four arms 9, 9, 9, 9, each made up of a pair 30 of angles 10, 10, such angles being riveted to the rectangular plate 11. Secured at the center of the spider is a block 11a, in which is keyed the shaft 12 by means of which the spider is rotated. The block 11 is held against downward movement with 35 respect to the shaft by means of the keeper plate 13 secured to the end of the shaft by means of the stud bolt 14. The shaft 12 is driven from an electric motor (not shown) which operates through suitable reducing gearing in the casing 40 15, the casing and motor being carried upon the deck 16 bolted to the under side of the I-beams 17.

A runner carrying the abrading means is carried at the end of each of the arms of the spider, the construction being shown in Fig. 1. The other 45 runners are similar to that shown in this figure, so that the illustration and description of one runner will be a sufficient disclosure of all. At the end of the runner is a block made up of two parts 18 and 19, which carries the shaft 20 of the 50 runner. The part 18 of the block lies between the pair of angles 10, 10 and is secured rigidly thereto by means of three bolts 20a. The part 19 of the block is secured to the part 18 by means of pairs of bolts 21, a bushing 22 for the shaft 20 being 55 clamped between the parts of the block and

further secured against movement by means of the set screw 23.

In order to adjust the vertical position of the runner, the shaft 20 is carried by the lever arm 24 pivoted at 25 between the pair of lugs 26 on the block 18, the other end of the lever resting upon a pin 27 carried by the bar 28, such bar being secured at its lower end to the block member 19. This bar is provided with a plurality of holes 29, as illustrated, so that the shaft 20 and the runner carried thereby may be adjusted down as the abrading elements wear away. In order to secure the upper end of the shaft 20 to the lever arm 24, clamping studs 30 are mounted 10 in the sides of the arm with their ends fitting into suitable recesses in the sides of the shaft.

The construction of the runner or support for the abrading elements will be seen by reference to Figs. 3 to 6 in connection with Fig. 1. The body of this runner or support consists of a pair 20 of opposing plates 31 and 32 clamped in the position shown by means of the bolts 33 which have their heads welded to the lower plate 32. The upper plate 31 is provided with a collar 34 and this collar is secured to a flange 35 on the lower end of the shaft 20 by means of the four bolts 36. The clamping blocks which carry the abrading elements each consists of three plates 37, 37 and 38 (Fig. 8) secured together by means of the 30 bolts 39. Perforations 40 are provided in the opposing faces of the plates, as indicated in Fig. 8 and in these openings or perforations are mounted the abrading elements 44. These abrading elements consist of sections 41 of wire cable made 35 up of strands of wire twisted together. The diameter of this cable is preferably about $\frac{3}{4}$ of an inch, but other sizes may be used if desired. Old worn out cable will serve just as well for this purpose as new cable, so that the cost of renewing 40 the abrading elements is relatively small.

The abrading action of elements of this kind has been found to be very satisfactory. The metal cable has about the right degree of hardness to cut the plaster without injury to the tables, and the sub-division of the elements, due to the plurality of strands which go to make up each section of the cable, give a plurality of cutting points which act very effectively to cut through the layer of plaster upon the tables as they are moved beneath the device. As the cable wears away, the shaft 20, supported upon the arm 24, is adjusted downwardly from time to time so that a large portion of the cable may be used before it is discarded. After the abrading sections have been worn down relatively close to 50 55

the lower plate 32, the clamping blocks may be released from between the plates 31 and 32 and turned upside down, thus permitting most of each section to be utilized. In practice, the spiders 5 are supported so that they may be shifted readily into and out of position and when replacement is required, little time need be lost in removing the spider and runners carried thereby and replacing it by another spider.

10 The plates 31 and 32 are provided with sets of perforations 42 and 43 which are of less dimension than the clamping members 31, 37 and 38 so that when the clamping blocks are positioned 15 between the plates, their margins are engaged thereby and clamped when the nuts on the bolts 33 are tightened. The perforations 42 and 43 are of such size that they will receive the sets of cable sections 41.

What we claim is:

20 1. Apparatus for cleaning plaster from plate glass surfacing tables mounted for movement along a track, said apparatus comprising a support mounted for rotation about a vertical axis and consisting of a pair of opposing perforated 25 clamping plates lying in horizontal planes, clamps lying between the plates at said perforations and having vertical openings therethrough, means for releasably securing the plates together with the clamps held therebetween, abrading members extending vertically through the perforations in the 30 plates and the openings in the clamps, said abrading members being held against vertical movement therethrough by said clamps, and means for adjusting the support downwardly as 35 said members are worn away.

2. Apparatus for cleaning plaster from plate glass surfacing tables mounted for movement along a track, said apparatus comprising a spider having radial arms, and rotatable about a vertical axis, a block at the end of each arm having 40 a vertical opening therethrough, a shaft extending through each opening, means for securing the shafts in a plurality of positions of vertical adjustment and holding them against rotation, a 45 support carried by each shaft consisting of a pair of opposing perforated clamping plates lying in horizontal planes, clamps lying between each pair of plates and having vertical openings therethrough, means releasably securing the plates 50 together with the clamps held therebetween, and abrading members extending vertically through the perforations in the plates and the openings in the clamps, said abrading members being held against vertical movement therethrough by said 55 clamps.

3. In combination in apparatus adapted for cleaning plaster from plate glass surfacing tables,

an abrading runner comprising a vertical spindle 5 engaging driving means, a support secured to the lower extremity of the spindle consisting of a pair of opposing perforated clamping plates lying in horizontal planes, means releasably securing the plates together, a plurality of clamping blocks provided with vertical openings therethrough positioned between the clamping plates at said perforations, flexible abrading elements extending vertically through the openings in the clamping 10 blocks, projecting a substantial distance from each face of said clamping blocks and held centrally against vertical movement by the clamping blocks, and means for adjusting the abrading elements downwardly as they are worn away. 15

4. In combination in apparatus adapted for 20 cleaning plaster from plate glass surfacing tables, an abrading runner comprising a vertical spindle engaging driving means, a support releasably secured to the lower extremity of the spindle consisting of a pair of opposing perforated clamping plates lying in horizontal planes, means releasably securing said plates in spaced relation, a plurality 25 of invertible clamping blocks provided with vertical openings therethrough positioned between the clamping plates at said perforations, said clamping blocks being of greater dimensions than the perforations in the clamping plates, and flexible abrading elements extending vertically through the openings in the clamping blocks, projecting a substantial distance from each face 30 of the clamping blocks and held centrally against vertical movement by the clamping blocks, the invertibility of which permits the upper portion of the abrading members to be brought into operative position when the lower portion thereof has 35 been worn away.

5. In an apparatus for cleaning plaster from plate glass surfacing tables mounted for movement along a track, a unit carrier having means 40 supporting it rotatably about a vertical axis, a pair of opposed plates disposed substantially horizontally and having registering openings extending therethrough, clamping jaws disposed between said plates and traversing the registering 45 openings therein, means for removably securing said plates rigidly in their opposed relation upon opposite sides of the clamping jaws carried therebetween, abrading members disposed between the clamping jaws and extending in opposite directions through the registering openings in the 50 plates above and below the latter, means for securing the clamping jaws rigidly upon the abrading members, and means for varying the elevation of the assembled plates and clamping jaws. 55

JOHN D. MCLEOD.

HARRY A. REYNOLDS.
